UNITED STATES PATENT OFFICE

114,764

DESIGN FOR A DESK

George De Motte Norman, Jasper, Ind., assignor to Hoosier Desk Company, Jasper, Ind., a corporation of Indiana

Application August 3, 1938, Serial No. 79,073

Term of patent 7 years

To all whom it may concern:

Be it known that I, George De Motte Norman, a citizen of the United States, residing at Jasper, in the county of Dubois and State of Indiana, have invented a new, original, and ornamental Design for Desks, of which the following is a specification, reference being had to the accompanying drawing, forming part thereof, in which:

Fig. 1 is a front perspective view of a desk showing my new design; and

Fig. 2 is a rear perspective view thereof.

The characteristic features of my design reside in the desk shown having flaring pedestal members of the configuration, proportions, and arrangement, as shown.

I claim:

The ornamental design for a desk, as shown and described.

GEORGE DE MOTTE NORMAN.
